UNITED STATES PATENT OFFICE.

FRANK BILLINGS, OF CLEVELAND, OHIO.

MINING AND LOADING APPARATUS.

1,095,786.

Specification of Letters Patent.

Patented May 5, 1914.

Application filed January 17, 1910. Serial No. 533,408.

To all whom it may concern:

Be it known that I, FRANK BILLINGS, a citizen of the United States, residing at Cleveland, in the county of Cuyahoga and State of Ohio, have invented a certain new and useful Improvement in Mining and Loading Apparatus, of which the following is a full, clear, and exact description.

The principal object of the present invention is to effect a substantial saving of time and money in removing the broken off material from in front of the working face or breast, in a mine, from which such material is broken. With an apparatus embodying, in a practical manner, my present invention, a train of cars may be brought in at one time by the mine locomotive, and these may be loaded wholly mechanically, and very much faster than shovels could load them. This relieves the miners of the necessity for doing any shoveling, and permits them to profitably employ their entire time in doing that which is required to be done to detach more material from the working face or breast. Moreover, a mine locomotive, handling the cars in trains can take care of more drifts than it can by handling them singly.

It is obvious that this invention may be embodied in a great variety of specific forms. The best embodiment known to me is that which is shown in the drawing, in which—

Figure 1 is a side elevation of the wheel truck, the hoe and its operating mechanism supported thereon, and of conveying mechanism for carrying the loose material from a point in front to the point behind the truck. Fig. 2 is a rear end elevation of said mechanism partly sectioned in the plane indicated by line 2-2 on Fig. 1. Fig. 3 is a plan view of the truck and the conveyer mechanism supported thereby. Fig. 4 is a plan view of the hoe and its operating mechanism which is supported upon said truck. Fig. 4^A is a plan view of base G.

I will now describe, with the necessary detail, the apparatus shown in said drawings, in which my invention is embodied.

Referring to the parts by letters, A represents a truck having wheels a² adapted to run on the regular mine tracks which are laid on the floors of the various drifts, tunnels, etc. This truck, as shown, comprises vertical side members a¹ and a horizontal platform a' connected to the tops of said side members and extending from one to the other. This truck supports a conveyer

which in the form shown is an ordinary conveyer. Depending from the platform a' to points below the axles of the wheels are the side members C, C of the conveyer frame, which frame extends from a point near the front end of the truck to a point a considerable distance behind the main truck body, the rearward extensions of said frame being supported by brace beams C'. The side members of the conveyer frame lie between the side members of the track frame, and may be connected therewith by transverse channel irons C².

The conveyer carrier B comprises a plurality of metal plates or sections b, which are connected at their sides with two sprocket chains b', said sprocket chains having friction rollers b² which may ride on the tracks c² carried by the side members C of the conveyer frame. At the front end of the conveyer frame is a transverse shaft 3² on which two sprocket wheels b⁴ are fixed. At the upwardly inclined rear end of the conveyer frame are longitudinally extended guide-ways c² for the reception of adjustable blocks b⁵ in which a transverse shaft b⁶ is mounted. Fixed to this shaft are two sprocket wheels b⁷.

The two sprocket chains run over the sprocket wheels b⁴ and b⁷. A transverse shaft b⁸ mounted in the side members of the conveyer frames carries a sprocket wheel b⁹ which is engaged by a sprocket chain b¹⁰, which in turn runs over another sprocket wheel b¹¹ on the shaft b⁶. The shaft b⁸ has a gear b¹² meshing with a pinion f on the shaft f' of an electric motor F carried by the conveyer frame; and it is through this mechanism that the conveyer mechanism is operated. Specially, there is nothing new about this conveyer mechanism. This particular type of a conveyer, even, is not essential to the present invention. It is only essential that the conveyer be suitable; that its front end be at the front end of the truck and that its rear end be behind the truck, so that the conveyer may carry the material past the truck; and that it or some adjunctive conveyer shall continue rearward above the tracks and at such elevation that the mine cars may go beneath it.

At the front end of the truck is an inclined apron Y whose upper end may be pivoted on a transverse axis to the side members of the truck, so as to overhang the conveyer belt, and so that its lower end may rest

upon the drift floor. Upon this truck, the hoe and its operating mechanism are supported. The base member G of this upper hoe supporting structure at its rear end rests upon and is pivoted on a vertical pivot stud J to an upwardly extended cross beam α^3 of the truck frame. At its front end this base members G carries rollers g which run upon a segmental track α^4 fixed to the top of the truck.

K represents the hoe shank which is slideable through a housing M which is connected on a horizontal pivot m with the base member G. Friction rollers m' carried by this housing support the hoe shank K. On the upper surface of the hoe shank are rack teeth which are engaged by a pinion n carried by the same shaft N to which the gear n' is fixed, this shaft being mounted on the housing M. An electric motor O fixed to the housing has a pinion o shown in dotted lines in Fig. 1 engaging with the gear n' whereby the latter and the shaft N may be turned with the result of moving the hoe shank forward or backward through said housing. This housing may be tilted upon its pivot so as to throw the front end of the hoe shank up or down as occasion may require, by means of a shaft P carrying a crank arm p, the end of which is connected by a link S with the base member G. The shaft P is mounted in the rear end of the housing M, and it is obvious that by rocking this shaft the housing may be tilted as described. This shaft may be turned by the mechanism shown, viz., a worm gear p' fixed to the shaft P, which is engaged by a worm r on the shaft r' of an electric motor R which is fixed upon said housing.

The base G and the parts carried thereby may be turned about the stud J on which said base G is pivoted by means of the following mechanism: A vertical shaft T is mounted in the base member G, and it has near its lower end a pinion t which meshes with the segmental rack α^5 which is a part of the previously mentioned segmental track. The upper end of this shaft T carries a worm wheel t' which is engaged by a worm u on the shaft u' of an electric motor U, which is carried by the base G.

To the front end of the hoe shank K a blade W may be fixed. Preferably its top edge engages with the lower face of said shank, and is provided with an upwardly extended boss w, to which is fixed a threaded stem or shank going through the hoe shank, and engaged by a nut w' so that as the nut is screwed onto this stem the blade W will be fixed in any desired angular position relative to said shank. It is evident from the foregoing description that an operator may by controlling the motors, have complete control of this hoe W and its movements. He may tilt the housing M so that

the hoe blade will engage with the floor of the drift; then he may cause said hoe to move endwise, and generally may cause the hoe to so move that it will drag the loose material on the floor of the drift to and up the apron so that it will be delivered onto the conveyer carrier. The rear end of this conveyer might be at such elevation that it would discharge directly into the mine cars. It is thought preferable not to extend the conveyer much behind the truck; but instead an auxiliary conveyer is provided onto which the rear end of the first conveyer may discharge its load; this auxiliary conveyer may extend upward and then rearward as far as is necessary.

Having described my invention, I claim:

1. In a loading machine, a frame adapted to be moved along a trackway, a conveyer extending lengthwise of the frame from the front end thereof, an inclined apron at the front end of the conveyer and extending upwardly and rearwardly from a plane below the conveyer, a tool shank adapted to be reciprocated inwardly and outwardly with respect to the frame, a support for said shank carried by the frame and capable of rocking movement about a substantially horizontal axis, and of swinging movement about a substantially vertical axis, said shank having means for receiving at its outer end a working tool and having a range of working movement which extends to the right and left of the longitudinal center plane of the machine, and above and below the horizontal axis about which said support is adapted to rock, and power mechanism for applying power to said shank for moving masses of material located at any point within the range of movement of the working tool toward the frame and up along the inclined apron by means of a combination of imparted movements which include a movement of the shank relative to its support, and one or both of the said movements of the support.

2. In a loading machine, a frame adapted to be moved along a trackway, a conveyer extending lengthwise of the frame from the front end thereof, an inclined apron at the front end of the conveyer and extending upwardly and rearwardly from a plane below the conveyer, a turn-table supported by the frame and movable about a vertical axis, a housing mounted on the turn-table for rocking movement about a horizontal axis, a tool shank mounted in said housing for reciprocating movement inward and outward with respect to the housing and provided at its outer end with a working tool; said shank having a range of working movement which extends to the right and left of the longitudinal center plane of the machine and above and below the horizontal axis about which the housing rocks, and power mecha-

nism for applying power to the said shank for moving masses of material located at any point within the range of movement of the working tool, toward the frame and up along the inclined apron, by means of a combination of movements which include a movement of the shank within the housing, and a movement of the housing about its axis of movement.

10 3. In a loading machine for use in mines, a frame adapted to move along a trackway, a conveyer extending through the frame lengthwise thereof, an inclined apron at the front end of the conveyer and extending upwardly and rearwardly from a point below the conveyer, a turn-table supported by the frame over the forward part of the conveyer and movable about a vertical axis which substantially intersects the longitudinal axis of 15 the conveyer, the conveyer, a housing mounted on the turntable for rocking movement about a horizontal axis, a tool shank mounted in said housing for reciprocating movement inward and outward with respect to the housing 20 and provided at its outer end with a working tool, said shank having a range of working movement which extends to the right and left of the longitudinal center plane of the machine and above and below the horizontal axis about which the housing rocks, 25 and power mechanism for applying power to the said shank for moving masses of material located at any point within the range of movement of the working tool, to- 30 ward the frame and up along the inclined apron by means of a combination of movements which include a movement of the shank within the housing, and a movement of the housing about its axis of movement. 35 4. In a loading machine, a frame adapted to be moved along a trackway, a conveyer extending lengthwise of the frame from the front end thereof, an inclined apron at the front end of the conveyer and extending 40 upwardly and rearwardly from a plane below the conveyer, a turn-table supported by the frame and movable about a vertical axis, a housing mounted on the turntable for rocking movement about a horizontal axis, 45 a tool shank mounted in said housing for reciprocating movement inward and outward with respect to the housing and provided at its outer end with a working tool, said shank having a range of working movement which 50 extends to the right and left of the longi- 55

tudinal center plane of the machine and above and below the horizontal axis about which the housing rocks, and power mechanism for applying power to the said shank for moving masses of material located at any point within the range of movement of the working tool, toward the frame and up along the inclined apron, by means of a combination of movements which include a movement of the shank within the housing, and a movement of the housing about its axis of movement, said power mechanism including three motors, one connected to the shank, another to the housing, and a third to the turn table.

5. In a loading machine, a frame adapted to be moved along a trackway, a conveyer extending lengthwise of the frame from the front end thereof, an inclined apron at the front end of the conveyer and extending upwardly and rearwardly from a plane below the conveyer, a turn table supported by the frame and movable about a vertical axis, a housing mounted on the turntable for rocking movement about a horizontal axis, a tool shank mounted in said housing for reciprocating movement inward and outward with respect to the housing and provided at its outer end with a working tool, said shank having a range of working movement which extends to the right and left of the longitudinal center plane of the machine and above and below the horizontal axis about which the housing rocks, and power mechanism for applying power to the said shank for moving masses of material located at any point within the range of movement of the working tool, toward the frame and up along the inclined apron, by means of a combination of movements which include a movement of the shank within the housing, and a movement of the housing about its axis of movement, said power mechanism including three motors, one connected to the shank, another to the housing, and a third to the turn table, the motors for reciprocating the shank and for rocking the housing being supported on the turn table.

In testimony whereof, I hereunto affix my 105
signature in the presence of two witnesses.
